Attorney.

UNITED STATES PATENT OFFICE.

GEORGE H. FAHRENBRUCH, OF OMAHA, NEBRASKA.

BRAKE-SHOE.

1,264,784.

Specification of Letters Patent. Patented Apr. 30, 1918.

Application filed December 11, 1917. Serial No. 203,594.

To all whom it may concern:

Be it known that I, GEORGE H. FAHRENBRUCH, a citizen of the United States, residing at Omaha, in the county of Douglas and State of Nebraska; have invented certain new and useful Improvements in Brake-Shoes, of which the following is a specification.

My invention relates to a new and useful improvement in brake shoes and particularly to that form of brake shoe known as the reinforced or steel back brake shoe.

As is well known in the art most of the brake shoes that are constructed today are made of cast iron having a reinforcing strip of steel, the said strip being formed with two longitudinal arms and a transverse piece or strip through which the key is passed to secure the brake shoe to the brake head. The general purpose of the steel back is, that it greatly reinforces the shoe and in case the same becomes cracked a part of the same cannot fall down under the wheel to cause serious accidents; in fact, the broken part will be held or will cling to the steel strip, and the brake shoe may then be removed at the end of the run.

Many forms of steel backs are in use and the object of my invention is to construct a steel back that will add greater strength to the brake shoe and tend to keep any part of the brake shoe from falling even though it becomes badly cracked or broken while in service.

Another object of my invention is to provide a plurality of lugs or keepers, as they might be termed, on the steel back through which the locking key is passed, instead of one lug or keeper as is the prevailing type now in use.

Still another object of my invention is to provide the reinforcing back with a plurality of the heretofore mentioned lugs or keepers and also to provide two reinforcing strips extending parallel with the longitudinal arms of the steel back through which the extra lugs or keepers are passed so that there is no possible danger of the lugs or keepers becoming torn from the said steel back.

With these and other objects in view my invention consists in certain new and novel features and combinations of parts as

will be hereinafter more fully described and pointed out in the claims.

55

In the drawings,

Figure 1 is a side view of my improved brake shoe showing the same attached to a conventional brake head.

Fig. 2 is a top plan view of the brake shoe.

Fig. 3 is an enlarged perspective of my improved reinforced steel back.

Fig. 4 is an enlarged sectional view taken through the center keeper or lug, and

65

Fig. 5 is a similar view taken through one of the additional keepers or lugs.

Referring now to Fig. 3 for the moment, I have shown a steel back comprising the two longitudinally extending arms 1 and 2 which may be stamped or otherwise formed from sheet steel having the center transverse lug or keeper 3 which may be fastened to the arms 1 and 2 in any manner desired.

Located a short way above the lug or keeper 3 is an additional keeper or lug 4 which extends between the two arms 1 and 2 and is then bent downwardly as at 5 and outwardly at each end as at 6. These arms 6 pass directly beneath the longitudinally extending arms 1 and 2, and extending parallel with the arm 1 is what I term a reinforcing strip 7 which has its ends 8 slit, which in turn are bent tightly around the arm 1. This reinforcing strip 7 is provided with two slots 9 and through the upper slot is passed the one end 6 of the keeper or lug 4. The end 6 extends slightly out beyond the face of the strip 7 so as to be embedded in the case shoe which will be shortly mentioned.

Positioned below the keeper 3 is another keeper or lug 10 which is similar in all respects to the lug 4, its one end 11 passing through the lower slot 9 in the reinforcing strip 7.

Also on the arm 2 is a reinforcing strip 12 which in all manners is similar to the strip 7, this arm being also provided with similar slots, so that the other ends of the arms 4 and 10 may pass through these slots and extend beyond the edge of the strip 12 so that they may be embedded in the cast shoe.

Secured near the ends of the arms 1 and 2 are also shown binding strips 13 and 14

which may be also used if desired to add rigidity to the steel back. This steel back is then placed in a mold (not shown) and around the same is poured the metal to form 5 a cast shoe as shown in Figs. 1, 4 and 5.

As may be seen in Fig. 5, by having the arms of the keepers 4 and 10 extend outwardly beyond the reinforcing strip, they present more surfaces to be embedded in the 10 shoe 15.

Referring to Fig. 1 for the moment, there is shown a conventional M. C. B. brake head showing my improved shoe secured thereto. By providing the additional keepers or lugs 15 as shown the central lug of course comes in its usual position while the upper additional lug comes directly under the brake hanger. The other lug, that is the lower one 10, will contact with the face of the brake head, the 20 three lugs forming the interlocking surfaces with the projections on the face of the brake head which is naturally more preferable than simply having the one central lug 3, which form is now generally in use.

25 Also by providing additional lugs or keepers such as 4 and 10, should the brake shoe crack transversely at a point beyond either center, it will be noticed that there is still an additional lug or keeper, either 4 or 30 10, to retain the shoe in position so that the same will not drop under the wheels as is sometimes the case where a brake shoe has only one central keeper or lug. Furthermore, the reinforcing strips will hold the 35 additional keepers 4 and 10 in position and even should the longitudinal arms 1 and 2 crack or break, still the reinforcing strips will tend to hold the shoe and reinforcing back together.

40 From the foregoing it will be seen that I have constructed a reinforced brake shoe having a particular form of steel back that in itself is stronger and more rigid than the ordinary back and furthermore by providing 45 additional lugs or keepers the brake shoe has three points of locking means instead of one, so that even should the brake shoe break transversely throughout any part of its length in all probability there will be one 50 holding means that will support the broken part until the end of the run or to such time as the same may be conveniently changed.

By providing the retaining lugs or keepers as shown in my construction, the shoe may be used with most, if not all, of the 55 M. C. B. heads now in general use.

Having thus described my invention, what I claim as new and desire to secure by Letters Patent, is:

1. A brake shoe having a steel back inserted therein comprising two longitudinally extending arms, a central lug or keeper extending between said arm, additional lugs or keepers located on either side of said central lug or keeper and a reinforcing strip connecting the two additional lugs or keepers. 60

2. A brake shoe comprising in part a steel back having two longitudinally extending arms, a central lug or keeper fastened to said 70 arms, additional keepers located above and below said beforementioned keeper or lug and two reinforcing strips located on the outer sides of said longitudinal arms, the ends of said additional keepers or lugs passing through said reinforcing strips and held in position thereby. 75

3. A brake shoe comprising longitudinally extending arms, a central lug or keeper secured to both of said arms, additional keepers located one on either side of said centrally located lug or keeper, reinforcing strips on each side of said longitudinally extending arms having their ends encircling said longitudinally extending arms and provided with slots therein, additional keepers located one above and one below said central keeper and having their ends passing under said longitudinally extending arm and through the slots in said reinforcing strips 90 and also extending out beyond said reinforcing strips. 85

4. A brake shoe comprising a shoe proper, a steel back embedded in the upper surface thereof, said steel back provided with a central lug or keeper and two additional keepers, reinforcing strips fastened to said back and also securing the additional keepers in position, end strips connecting the two said arms, one of said additional keepers adapted to come directly beneath the brake hanger when said shoe is placed on a brake head. 95

In testimony whereof I affix my signature.
GEORGE H. FAHRENBRUCH.
